CABINET FOR AN ELECTRONIC APPARATUS

Earl K. Stewart, Scotia, N.Y., assignor to
General Electric Company

Filed June 23, 1971, Ser. No. 156,148

Term of patent 14 years

Int. Cl. D13—03

U.S. Cl. D26—5

FIG. 1 is a front elevation of a cabinet for an electronic apparatus showing my new design;

FIG. 2 is an end elevation thereof;

FIG. 3 is an end elevation taken from the opposite side of FIG. 2;

FIG. 4 is a rear elevation thereof; and

FIG. 5 is a side elevation thereof, the opposite side being substantially the same in appearance.

I claim:

The ornamental design for a cabinet for an electronic apparatus, substantially as shown and described.
